UNITED STATES PATENT OFFICE.

ARTHUR BERNHARDT GURICKE, OF GLASHÜTTE, GERMANY.

TRAVELING-CASE FOR TYPE-WRITING MACHINES, CALCULATING-MACHINES, AND THE LIKE.

1,062,277.

Specification of Letters Patent.

Patented May 20, 1913.

Application filed September 7, 1910. Serial No. 580,872.

To all whom it may concern:

Be it known that I, ARTHUR BERNHARDT GURICKE, a citizen of the Empire of Germany, residing at Glashütte, in the Kingdom of Saxony and German Empire, have invented certain new and useful Improvements in Traveling-Cases for Type-Writing Machines, Calculating-Machines, and the Like, whereof the following is a specification.

The object of the invention is to provide a compact traveling case adapted in closed position for carrying the machine by hand and in open position to serve as a rest for the machine in use.

Figure 1 of the accompanying drawings represents a longitudinal vertical section of a traveling case embodying one form of this invention adapted for a typewriter machine. Fig. 2 represents a front elevation thereof in closed position. Fig. 3 represents a plan view in open position of the traveling case shown in Figs. 1 and 2.

The same reference numbers indicate corresponding parts in all the figures.

The traveling case is particularly adapted to contain a typewriter. In this form of embodiment the bottom plate 33^a is provided with the upright flange or backboard 38. This bottom plate is provided with recesses 35. In this embodiment the end plates are also divided into stationary and folding parts. These stationary parts 40 which close the ends of the spring roller compartment and which have journal bearings for supporting the spring roller 39 terminate immediately in front of said spring roller and the folding parts 34 of said end plates are hinged directly to the bottom plate 33^a by hinges 10'. The outer corners of the lower edges of these hinged parts are rounded off to fit the recesses as indicated in Fig. 2 when in open position. These hinged parts are provided on their inner faces adjacent to their upper edges with curved guideways 36.

A roll top 37 is connected at its inner end with the spring roller 39 and provided at its outer end with a transverse bar 49 which slides in the grooves 36 together with the ends of the roll top 37. When the hinged end parts 34 are swung open they form with the base plate 33^a a wide plate and constitute desk-like spaces at opposite sides of

the typewriter for holding manuscript, paper and other implements of work. The spring roller is disposed above the base plate in a compartment at the rear thereof. The relation of said compartment and the spring roller to the base plate is such as to constitute a compact traveling case. This spring roller tends continuously to wind up the roll top.

In order to hold the sides firmly in upright position, on each side is arranged a spring pressed pawl 41, which is adapted to be moved about a pin 42 at right angles to the sides. The spring pressed pawl has a handle 43 projecting at an angle from the side and which is adapted to move on a guiding pin 44. A spring 45 is wound around the guiding pin 44, acting continuously thereon, so that the handle 43 is pressed away from the side. The pawl is further provided with a horizontal arm 46 provided with a cut-away portion. With this cut-away portion the arm engages, in the operative position of the spring pressed pawl, with a lug 47 which is secured to the upper transverse bar 48 of the rear portion 38. The lug 47 is provided with an inclined portion in such manner that the spring pressed pawl on the sides being folded up engages with the lug, while for the purpose of depression of the sides a backward movement of the handle 43 is sufficient.

At the forward end of the roll top 37 is provided a bar 49, the lateral ends of which, on bringing the sides into upright position, engage again in the guiding groove 36. The bar 49 is preferably provided with an inclined face 50 in order on the roll top being wound up, to effect a braking action on the roll top, by coöperation with an inclined face 51, arranged on the rear wall of the casing. In this construction the winding roller for the roll top is supported above the portable base plate in the fixed parts of the end plates whereby a compact traveling case is secured.

I claim as my invention:

A calculator or typewriter traveling case comprising a portable base plate adapted to receive the machine, divided end plates composed of fixed parts having journal bearings and hinged parts having grooved ways, means for holding said hinged parts in upright position, a spring roller supported

105

above said base plate in bearings of the fixed parts of the end plates, and a flexible roll top connected at its rear with said spring roller and movable at its opposite 5 ends in said grooved ways of the hinged parts of said end plates.

In testimony, that I claim the foregoing

as my invention, I have signed my name in presence of two subscribing witnesses.

ARTHUR BERNHARDT GURICKE.
